UNITED STATES PATENT OFFICE.

JOHN E. GREENAWALT, OF DENVER, COLORADO.

PRECIPITATING APPARATUS.

No. 906,011.

Specification of Letters Patent.

Patented Dec. 8, 1908.

Application filed April 3, 1905. Serial No. 253,622.

To all whom it may concern:

Be it known that I, JOHN E. GREENAWALT, a citizen of the United States, residing in the city and county of Denver and State of Colorado, have invented certain new and useful Improvements in Precipitating Apparatus; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in apparatus for precipitating metallic values from their solutions, being especially adapted for the precipitation of gold and silver from chlorin or other solutions but being 20 more especially intended for use where chlorin is used in the leaching process for dissolving the metallic values.

The apparatus consists of one or more cells each of which is provided with a perforated diaphragm located in its lower portion upon which is placed a mass of lead shavings provided with a small proportion of zinc alloy, say from one-half of one per cent. to one per cent. In the upper part of 25 each cell is suspended a porous jar containing the anode element of the electrolytic cell; the aforesaid mass of lead shavings with its alloy zinc, forming the cathode element. The positive wire of an electrical 30 source is connected with the anode element; while the negative wire of the source is connected with the cathode element. As a convenience in connecting the negative conductor with the cathode element, a metal 35 ring is placed upon the perforated diaphragm beneath the lead shavings.

The solution containing the metal values to be precipitated, is introduced to the cell below the perforated diaphragm and caused 40 to pass upwardly therethrough, through the mass of lead shavings and if desired out at the top into a conduit leading to the lower part of another cell through which the solution is passed. In this way the solution 45 may be passed through any desired number of precipitating cells.

In carrying out the process in connection with this apparatus, the electric current is passed through the solution in the opposite 50 direction from the passage of the solution itself.

Having briefly outlined my improved construction, I will proceed to describe the same in detail reference being made to the accompanying drawing in which is illustrated 60 an embodiment thereof.

In this drawing, Figure 1 is a vertical longitudinal section taken through a number of cells connected in accordance with my invention. Fig. 2 is a top plan view of the 65 same. Fig. 3 is a detail view of the perforated diaphragm or floor employed in connection with the cells. Fig. 4 is a detail view of a ring employed in connection with the cell.

70 The same reference characters indicate the same parts in all the views.

Let A, B, and C designate three precipitating cells which are connected in such a manner that the solution to be treated may 75 be passed through the same in succession. In the lower part of each of these cells is placed a porous floor or diaphragm 2. Upon this floor is placed a mass of metal shavings 3 preferably lead shavings provided with an 80 alloy of from one-half of one per cent. to one per cent. of zinc. This mass of metal shavings constitutes the cathode element of the electrolytic cell.

In the upper part of each cell is suspended 85 a porous jar 8 by means of rods D which rest upon the tops of the cells as best illustrated in Fig. 2. Within each of these cells is placed an anode element 7 preferably composed of carbon. The positive wire 6 90 of an electrical source is connected with each anode element; while the negative wire 9 of the source is connected with the cathode element. In order to form proper contact with the wire 9, the metal ring forming an 95 electrode is located on the perforated floor. The wire 9 is directly connected with this ring in the manner best illustrated in Fig. 4, as by coiling the wire around the ring. The metal shavings being in direct contact 100 with the ring, a good electrical connection is made between the wire and the cathode element. Each jar 8 is partially immersed in the solution of the cell when the latter is in use. Each jar also contains a quantity 105 of liquid, to facilitate the passage of the electric current through the jar into the solution. Each jar is provided with ears 10 on opposite sides through which the rods D pass.

110 From the foregoing description the use and operation of my improved apparatus

will be readily understood. The solution G from the leaching tank (not shown), is delivered to the cell A by a conduit 1, the solution entering the cell below the perforated floor 2. The source of supply with which the pipe 1 is connected, is located sufficiently above the cell A to cause the liquid to travel upwardly in the cell, the solution first passing through the perforated 5 floor, and then upwardly through the metal shavings. If a number of cells is used in connection with each other, this liquid will overflow and pass out into a conduit 1^a connected with the upper part of the cell. 10 This last named conduit enters the cell B below the perforated floor and the solution passes upwardly through the cell B in the same manner as heretofore explained with reference to the cell A. The solution may 15 be taken from the upper part of the cell B and delivered through a conduit 1^b, to a cell C, the liquid being delivered below the perforated floor in the same manner as in the other cells. In this way the liquid may 20 be made to travel from the bottom of each cell upwardly, any desired number of cells being employed. The solution after passing through the last cell of the series, passes 25 out of a conduit 1^c and may be delivered to any desired location.

Simultaneously with the passage of the solution through the various cells from the bottom upwardly, the electric current enters each cell by the positive wire 6 passing 30 first through the anode element, thence through the porous jar, thence through the solution contained in the cell, to the cathode element and thence out through the negative wire 9 to the other pole of the source.

40 It is preferred to heat the solution to a temperature of one hundred and thirty degrees Fahrenheit or greater since the precipitation of the values is facilitated by this step. The process of precipitation, however, herein described, is not claimed in this application but by an application filed April 45 3rd, 1905, Serial No. 253,621.

By virtue of the process heretofore explained, the metallic values are precipitated 50 as a black pulverulent slime consisting principally of lead, silver and gold which is readily melted into bullion and the metal separated. The lead is then also melted, a suitable amount of zinc added, and cut into 55 shavings when it is again ready for use.

Having thus described my invention, what I claim is:

1. In a precipitating apparatus, the combination of a cell having a perforated floor 60 located therein and supported above the bottom thereof, a mass of shavings cut from an alloy of lead and zinc supported by the floor and forming a cathode element, a porous jar suspended from the top of the cell

and projecting thereinto, the said jar being 65 provided with an anode element, suitable electrical connections with the anode and cathode elements, and means for introducing the solution to be treated into the cell below the perforated floor and forcing the solution 70 upwardly through the said floor and through the metal shavings thereof in a direction opposite the passage of the electrical current through the cell, substantially as described.

2. In a precipitating apparatus, the combination of a cell having a perforated floor located therein and supported above the bottom thereof, a mass of metal shavings cut from an alloy of lead and zinc supported by the floor and forming a cathode element, 75 an anode element suspended from the top and projecting into the electrolyte of the same, suitable electrical connections with the anode and cathode elements, and means for introducing a solution to be treated into the 80 cell below the perforated floor and forcing the solution upwardly through the said floor and through the metal shavings thereon in a direction opposite to that of the electric current through the cell, substantially as 85 described.

3. In a precipitating apparatus, the combination of a cell provided with a perforated floor mounted above the bottom, a metallic sponge or mass of metallic shavings formed 90 from an alloy of lead and zinc mounted on the perforated floor, a porous jar suspended from the top of the cell and projecting thereinto, means for passing the solution to be precipitated through the floor and metallic shavings or sponge, and means for passing an electric current through the porous jar into the solution and then into and among the metallic sponge, substantially as 95 described.

4. In a precipitating apparatus, the combination of a cell provided with a perforated floor mounted above the bottom and dividing the cell into an upper and lower compartment, a metallic sponge or mass of metallic shavings mounted upon the perforated floor, and the same having been cut from an alloy of lead and zinc, a porous jar suspended from the top of the cell and projecting 100 thereinto, means for introducing a solution into the lower chamber and thence through the metallic sponge, and means for introducing an electrical current through the porous jar into the solution and then into and among the metallic sponge, the metallic 105 sponge constituting the cathode of the arrangement.

In testimony whereof I affix my signature in presence of two witnesses.

JOHN E. GREENAWALT.
